PACKING BRACE
Verne G. Bjerum, 2452 Lovejoy St., Pomona, Calif.
Filed Aug. 6, 1962, Ser. No. 214,993
2 Claims. (Cl. 206—46)

This invention relates generally to the packing of items for shipment, and more particularly to the packing of devices, such as automatic washing machines, having movable elements therein, such as the agitator and tub.

While the automatic washing machine has been a great advance to homemakers, it has created new problems for those concerned with the packing and shipping of such machines. Thus, in those machines making use of an agitator in a rotatable tube, it is customary for the tub and agitator to have a certain degree of freedom of movement in a plane perpendicular to the axis of rotation. The restrained freedom thus provided is intended to prevent excessive vibration when an unbalanced tub is rotated at high speed to extract the water from the laundry. When the washing machine is being shipped, however, this same restrained freedom permits the tub to hit against mechanical stops, thus damaging the tub and possibly the attached motor and agitator.

Heretofore transportation organizations, such as moving and storage companies, etc., have attempted to solve the problem by fitting a generally circular retaining member into the upper end of the washing compartment, but this has required that such companies maintain a stock of different size and differently shaped retaining members for the different machines. The retaining members themselves are not inexpensive, and the problem of maintaining an adequate stock is a difficult one. Furthermore, the circular retaining members have no provisions for folding, and hence they present a storage problem.

It is therefore a major object of this invention to provide an improved packing or bracing means for relatively movable objects.

Another object of the invention is to provide such a packing or bracing means that can be adapted to a wide variety of uses and applications.

It is a further object of the invention to provide such a bracing means that is relatively inexpensive to use, yet is sufficiently strong to support a relatively heavy object subject to the normal impact and vibration of freight handling.

Still another object of the invention is to provide such a bracing means that is adjustable to machines and devices of different sizes and shapes, thereby simplifying warehousing problems for the users of such bracing means.

It is a still further object of the invention to provide such a bracing means that is inexpensive to make, store, and use, while producing superior results.

These and other objects and advantages of the invention will become apparent from the following description of a preferred and optional form thereof, and from the drawings illustrating those forms in which:

FIGURE 1 is a fragmentary perspective view of the upper end of an automatic washing machine showing the installation of the preferred form of bracing means in such a washer;

FIGURE 2 is a plan view of the bracing means installed in such a washing machine, the latter being shown in a fragmentary form;

FIGURE 3 is a side elevational view of the two sepa-

2

rate elements that go to make up the bracing means of the preferred form;

FIGURE 4 is a perspective view of the preferred form of bracing means and related elements as they appear when assembled in an individual package;

FIGURE 5 is a side elevational view of the devices used to make up the optional form of bracing means;

FIGURE 6 is a perspective view of the bracing means and related equipment of the optional form, enclosed 10 in its corresponding package; and

FIGURE 7 is an end elevational view of a fragment of one of the bracing members, showing the form of material used.

Considering the figures and particularly FIGURE 1 15 thereof, the numeral 10 indicates generally an automatic washing machine of the top loading type having an agitator 11 mounted for rotation in a tub 12, which tub is also mounted for movement within the machine 10. The agitator 11 and tub 12 are so mounted that the 20 two are movable as a unit in a horizontal plane, thus reducing the noise and vibration imparted by the machine to the floor, and reducing the wear on the bearings. As previously mentioned, it is this horizontal movement, which is restrained by resilient snubbing means 25 (not shown), that causes problems when the washing machine 10 is shipped. However, by restraining the movement of either the agitator 11 or the tub 12, movement of the other will likewise be restrained.

To provide this restraint, two sets of bracing members are used, these bracing members engaging the agitator 11, the tub 12, or both, and bracing them against a depending flange 13 that extends downwardly around the opening of the washing machine 10.

As indicated in FIGURES 1 and 2, the bracing takes 35 the form of inter-fitting strips of sheet material that engage the agitator 11 at their center, and engage the depending flange 13 at their ends. Thus, a pair of strips 14, notched at the center, extend from left to right across the opening of the washer, the strips being placed so 40 that the notch is in the upper edge of the strips. One strip 14 is placed on the forward side of the agitator 11, while the other strip 14 is placed on the rear side of the agitator, and the strips are urged together to engage the sides of the agitator, and are forced downwardly to wedge firmly within the flange 13. Similar strips 15, likewise provided with a central notch, extend from the front to the rear of the flange 13 and engage the sides of the agitator 11 in much the same way that the strips 14 do. The strips 15 have the notch on their 45 lower sides, so that the cooperating notches in the strips 14 and 15 permit the strips to fit within a smaller space. The upper strips 15 are likewise wedged into the flange 13, and pressed firmly against the agitator 11, thus holding and bracing the agitator and the associated drum 12 against forward and backward, and lateral movement.

To hold the braces 14 and 15 firmly in position where they clamp the upper end of the agitator 11, and to prevent bowing of these braces, the various elements are 50 urged together by a tension material, such as a strong pressure sensitive tape. Commercially available tapes, such as those having a plurality of longitudinally extending fibers of a material such as glass, are very satisfactory, and the tape 16 is preferably wrapped around the 55 upper and lower pieces 14 and 15 in such a manner that all of the pieces are compressed or directed inwardly, toward the center of the agitator 11, as shown in FIGURES 1 and 2. While a pressure sensitive tape is very satisfac-

tory for the purpose of binding the pieces 14 and 15 together and to the agitator 11, it will be appreciated that rope, twine, or other flexible material including various forms of tape, can be used with equally good results.

While the pieces 14 and 15, which form the braces for the agitator 11 and tub 12, may be formed of any of a variety of materials, it has been found preferable to form these pieces of a heavy corrugated paper construction. Thus, as indicated in FIGURE 7, in which a fragment of one of the braces is illustrated, the brace preferably consists of a plurality of layers of heavy paper separated by layers of corrugated paper. This is the same general form of construction as is used in heavy cardboard boxes, sometimes referred to as corrugated boxes, but the present material is substantially thicker than the wall of the average box. For example, it has been found that very desirable and satisfactory results are obtained if the pieces 14 and 15 are of a thickness of approximately $\frac{3}{4}$ to 1 inch thick. Preferably the corrugations run the length of the pieces 14 and 15, so that they add materially to the strength of the piece, instead of being run crosswise of the piece, in which case there would be a tendency for the pieces to bow or even bend when they are forced into the machine.

One of the advantages of using corrugated paper will become apparent when it is realized that in order for the bracing means to fit the great majority of washing machines, it is necessary for the pieces 14 and 15 to be made large enough to fit the largest machine, and then to cut the pieces until they fit the particular machine being packed. The corrugated paper can be cut with a pocket knife, and to aid in cutting the end of the brace 14 or 15, marks 17 are placed on each of the ends. It will be noted that the marks 17 are stripes extending across the braces 14 and 15 and angularly positioned with respect to the ends. Thus, if a cut is made along the edge of one of the stripes, and a corresponding cut is made along the edge of the corresponding strips along the other end, a generally trapezoidal shape is formed. As a result, when the pieces 14 and 15 are pushed as far into the machine as is practical, the pieces will be held in place by a wedging action. If the lower braces 14, for example, are placed generally in the proper location extending across the top of the opening of the washing machine, the closest line within the opening to the machine may be followed and the bracing pieces 14 cut to the proper length. Because of the tapered effect, the bracing pieces 14 and 15 may easily be inserted in the opening, and the further movement of these braces into the opening will produce a wedging effect that will securely hold the braces, the agitator 11, and the tub 12.

One of the advantages of the use of the notched braces 14 and 15 is that the ends of the braces bear against the same portions of the washing machine. Thus, if the ends of the lower braces 14 bear against the depending flange 13, it will be clear that the ends of the upper braces 15 will likewise bear against the same depending flange. If the ends of the braces 14 bear against the tub 12 and the depending flange 13, the ends of the braces 15 will likewise bear against the same tub and depending flange. If the braces 14 and 15 were both straight sections, without any notches, the lower braces 14 would bear against one area, and the upper braces would bear against another area. Thus, it is possible that the lower braces might bear against the tub 12, while the upper braces might bear against the depending flange 13. This is clearly an undesirable condition.

Nevertheless, it is possible in many instances to make one of the braces, such as the upper braces 15, a straight section without any notches, narrow enough to fit within the notch of the lower braces 14. Such a combination is shown in FIGURE 5. In this combination, the lower braces 14 are similar to those shown in FIGURE 3, but the upper braces, 15a, are narrower and without the notch had by the braces 15 shown in FIGURE 3. The upper

braces 15a consequently do not cover the entire vertical area covered by the lower braces 14, and they do not cover area that is not covered by the lower braces. Thus, if the braces 14 engage only the depending flange 13, the upper brace 15a will likewise engage only the depending flange. Under these conditions, the braces 15a are usually sufficient, are lighter in weight, and can be made for a smaller price. Consequently, a package containing this combination, such as shown in FIGURE 6, can be sold for less than a pack containing the braces shown in FIGURE 3.

As indicated in FIGURES 4 and 6, the entire group of elements going to make up the necessary combination of lower braces 14, upper braces 15 or 15a and tape 16 can be packaged in a very small space, and readily stored. The combination or pack is of light weight, and has the advantage that a single pack can fit substantially all of the automatic washers presently in use. The cost of manufacturing the braces is relatively inexpensive, since there is no special fabricating work to be done other than what can be done by a simple die or cutting tool. The installation of the bracing means is simple and quick, and provides the necessary strength and protection.

From the foregoing, it will be seen that there has been provided a bracing means fully capable of achieving the objects and securing the advantages heretofore set forth. While a preferred and optional form has been described, the invention is not to be restricted to the particular form or arrangement of parts herein described and shown, except as limited by the following claims.

I claim:

1. Bracing means of the class described for use in securing an element movably mounted within a housing, which includes:

a first pair of brace members extending across said element and engaging said container, the length of said brace members being greater than the housing distance spanned, whereby said brace members are placed under compression, said members being of a rigid corrugated paper construction capable of being shaped by a pocket knife, the ends of said braces having converging lines marked thereon to aid in cutting said braces to a corresponding tapering shape, said braces having a centrally located notch extending along one edge;

a second pair of brace members extending across said element generally perpendicularly to said first pair of brace members, and engaging said housing, the length of said second pair of brace members being greater than the housing distance spanned thereby, whereby said second pair of brace members are placed in compression, said second pair of brace members being of a rigid corrugated paper construction capable of being shaped by a pocket knife, the ends of said braces having converging lines marked thereon to aid in cutting said braces to a corresponding tapering shape, said second pair of brace members fitting within the notch in said first pair of braces; the lower surfaces of said crossed brace members being substantially planar and being spaced a substantial distance from the lower portion of said element; and flexible tension means around said first and second pairs of braces and holding said braces together and to said element.

2. Bracing means for securing the agitator and rotatable hub of an automatic washing machine against movement during shipment, which includes:

a pair of lower braces formed of corrugated paper material, said braces having a centrally located notch in their upper surfaces, the ends of said braces having downwardly converging lines marked thereon to aid in forming a pair of braces having downwardly tapering ends, said braces being capable of being shaped by a pocket knife;

a pair of upper braces formed of corrugated paper

material, said braces having a centrally located notch in their lower surfaces whereby the notch areas of said upper and lower braces may interfit, the central areas of said braces engaging and holding said agitator, the ends of said upper braces having downwardly converging lines marked thereon to aid in forming a pair of braces having downwardly tapering ends, said upper braces being capable of being shaped by a pocket knife, said upper and lower braces being substantially perpendicular to each other; and flexible tension means around said upper and lower braces and holding said braces together and to said agitator.
